UNITED STATES PATENT OFFICE.

JOHN PRESSLEY COLEMAN, OF EDGEWOOD PARK, PENNSYLVANIA,
ASSIGNOR TO THE UNION SWITCH AND SIGNAL COMPANY, OF
SWISSVALE, PENNSYLVANIA.

RELAY.

SPECIFICATION forming part of Letters Patent No. 625,146, dated May 16, 1899.

Application filed May 25, 1898. Serial No. 681,710. (No model.)

To all whom it may concern:

Be it known that I, JOHN PRESSLEY COLEMAN, a citizen of the United States, residing at Edgewood Park, in the county of Allegheny and State of Pennsylvania, have invented or discovered certain new and useful Improvements in Relays, of which improvements the following is a specification.

The invention described herein relates to certain improvements in double-pointed relays.

In the construction forming the subject-matter of application, Serial No. 667,265, filed January 20, 1898, it will sometimes occur when the magnets are feebly energized and one end of the armature is nearer its pole of the magnet than the opposite end of the armature to its pole that only the former end of the armature will be attracted, so that only one circuit will be closed.

The object of the present invention is to insure the movement of both contact-plates against their contact-points under all conditions when the magnets are energized.

It is a further object of the invention to protect the relay as against injury from lightning or other abnormally heavy currents.

The invention is hereinafter more fully described and claimed.

In the accompanying drawings, forming a part of this specification, Figure 1 is a sectional elevation of my improved relay, the plane of section being indicated by the line I I, Fig. 2. Fig. 2 is a plan view of the under side of the relay. Figs. 3 and 4 are sectional elevations, the planes of section being indicated by the lines III III and IV IV, respectively, in Fig. 2. Fig. 5 is a view similar to Fig. 4, illustrating a modification of my improvement; and Fig. 6 is a top plan view of the relay.

In the practice of my invention the magnets are held in position with their lower ends projecting through the top plate 2 by means of bolts 3, having one end connected to the supporting-frame 4 of the magnets and their opposite ends secured in the top plate 2. The armature 5 is secured to a lever 6, attached to a pin or shaft 7, whose conical ends are mounted in similarly-shaped holes in the ends

of supporting-pins 8, screwing through lugs 8^a, formed on the under side of the top plate 2. On the under side of the lever 6 are formed lugs, one of which is provided with a conical hole for the reception of one end of the pin 9, 55 while the opposite end of said pin is mounted in a hole in the end of a screw 9^a, passing through the other lug on the armature-lever. As clearly shown in Figs. 1, 2, and 3, the pin 9 is mounted at right angles to the armature, 60 so that a plate 10, secured to said pin midway of its length, will lie parallel to but below the armature 5. To the ends of the plate 10 are secured the contact-plates 11 11^a; but the latter are insulated from the plate 10. These 65 resilient contact-plates are so proportioned as regards their length that when the armature is attracted to the magnet they will be drawn against the contacts 13 and 13^a, which are preferably constructed in the form of 70 binding-posts passing through the top plate 2, but insulated therefrom. The lower ends of these posts are provided with sockets or recesses for the reception of carbon blocks 14, adapted to serve as contact-surfaces for 75 the posts. It is preferred to coat these carbon blocks, except the contact-face, with copper or other conducting material and to secure them in position in the binding-posts by solder. The back contacts for the contact-plates 8, 11 and 11^a are formed by screws 15 and 15^a, passing through bars 16 and 16^a. As shown in Figs. 1 and 2, one end of these bars is supported in but insulated from a bracket 17, formed on the lower side of the top plate 2. 85 The opposite ends of the bars are secured to the lower ends of the binding-posts 18 18^a, passing through but insulated from the top plate 2.

In lieu of securing the contact-plates 11 and 11^a rigidly to the carrier-plate 10 one or both thereof may be pivotally mounted to the carrier-plate, as shown in Fig. 5. A desirable construction for so connecting the contact-plates to the carrier-plate consists of an arm 95 19, secured to the plate 10 adjacent to its end, and a block 20, secured to the contact-plate 11, said arm and block being pivotally connected together by a pin 21. As shown in Fig. 5, the block 20 is between the outer or 100

left-hand end of the contact-plate and the pivotal pin 21, so that the rear or right-hand end of the contact-plate will be normally held by the weight of the block against the carrier-plate 10, but is prevented from making electrical connection therewith by insulating material on the under side of the plate 10 or upper side of the contact-plate.

It is customary to arrange a shunt-circuit, 10 which may be closed whenever the magnets 1 are deenergized or may be closed only when the magnets are deenergized and the front or operative end of the contact-plate sticks or is welded to its contact-point. When it is desired to 15 close the shunt-circuit on each reverse movement of the armature, the contact-pins 15 and 15^a are arranged on the bars 16 and 16^a, as shown in Fig. 4, and are provided by preference with platinum points. When the shunt-cir- 20 cuit is to be closed only in case of the adherence of the contact-plates to their front points, the pins 15 and 15^a have their points formed of insulating material, and additional contact-points 22, provided with platinum points, are 25 passed through the bars 16 and 16^a, so that when the contact-plates turn on their pivotal supports they will come in contact with these additional back contacts, as clearly shown in Fig. 5. In case it is desired to close the 30 shunt-circuit in the construction shown in Fig. 5 every time the magnet is deenergized, whether the contact-plate is fused to its front contact or not, the pins 15 22 are provided with platinum contact-points and both pins 35 are included in the shunt-circuit.

The binding-posts 13 13^a 18 18^a and the binding-posts 23 23^a and 24 24^a for the track

and signal circuits are secured, as heretofore stated, in the top plate, but insulated therefrom. In order to protect the relay from 40 lightning or other abnormally-heavy currents, disks 25 with serrated edges are secured upon the binding-posts, as clearly shown in Fig. 5. These posts are made of such a diameter that the points of the disk on one post will be ad- 45 jacent to but not in contact with the points of a disk on the adjacent binding-post, and the air-gap should be such as to prevent the passage of a normal current, but not to present too great a resistance to abnormal currents. By loosening the clamping-nuts which hold these disks in position the latter can be adjusted around so as to bring new points into position when other points have been burned away. 55

I claim herein as my invention—

1. A magnet having in combination therewith a pivotally-mounted lever having an armature secured thereto, a carrier-plate pivotally mounted with a freedom of automatic 60 movement on the armature-lever, and contact-plates attached to said carrier-plate, substantially as set forth.

2. A magnet having in combination a pivotally-mounted armature-lever, a carrier-plate 65 pivotally mounted on said lever, and contact-plates pivotally mounted on the carrier-plate, substantially as set forth.

In testimony whereof I have hereunto set my hand.

JOHN PRESSLEY COLEMAN.
